RAILWAY CAR JOURNAL HOISTING
APPARATUS

August W. Donop, Chicago, Ill., assignor to
Portable Plating and Equipment Company,
Chicago, Ill., a corporation of Illinois

Application August 8, 1938, Serial No. 223,607

2 Claims. (Cl. 254—34)

My invention relates, generally, to hoisting or lifting apparatus and it has particular relation to railway car journal hoisting apparatus.

The object of my invention, generally stated, is to provide railway car journal hoisting apparatus for removing journal brasses from all types of railway cars, wherein a journal box is jacked up from beneath and the load of the lifted journal box is supported on the top of the railway car wheel the axle of which is journaled in the lifted journal box.

Other objects of my invention will in part be obvious and in part appear hereinafter.

Accordingly, my invention is disclosed in the embodiment shown in the accompanying drawings, and it comprises the features of construction, combination of parts and arrangement of elements which will be exemplified in the construction hereinafter set forth and the scope of the application of which will be indicated in the appended claims.

For a more complete understanding of the nature and scope of my invention, reference may be had to the following detailed description, taken in conjunction with the accompanying drawings, in which:

Figure 1 is a top plan view of an arm member adapted to fit on a railway car wheel and to support a journal box by a cable hung over its outer end;

Figure 2 is a vertical section taken on line 2—2 of Figure 1;

Figure 3 is an enlarged vertical section taken on line 3—3 of Figure 1;

Figure 4 is an end view of the wide end of the arm member of Figure 1;

Figure 5 is a top plan view of a stirrup and a ladder fastening member showing a cable joining one end of the stirrup to one end of the ladder fastening member;

Figure 6 is a bottom view of the stirrup of Figure 5;

Figure 7 is a vertical section taken on lines 7—7 of the ladder fastening member of Figure 5;

Figure 8 is a view partly in section taken on the side of the journal box of a railway car wheel showing my journal hoisting apparatus with jack, assembled to lift the journal box;

Figure 9 is a view taken on the end of the journal box of Figure 8 and showing the journal box lifted and the journal brass wedge and journal brass ready to be removed; and

Figure 10 is a view partly in section taken on the side of the journal box of a railway car

wheel showing the use of part of my journal hoisting apparatus employed in the conventional manner of jacking up a journal box.

Referring now to Figure 1 of the drawings, the reference character 11 designates an arm member which is preferably made of steel. The outer end 12 has a groove 13 formed thereon as shown. In order to hold the arm 11 on a railway car wheel, the arm 11 has its inner end, or the upper end in Figures 1 and 2, formed into a hook 14 which is adapted to fit over the flange of a railway car wheel 15, as shown in Figure 3 of the drawings. A hardened steel piece 16 may be set in the end of the hook 14 with teeth formed on it for gripping into the inside of the car wheel 15. A bearing surface 17 is formed on the underside of the arm member 11 which is adapted to bear on the tread 18 of the car wheel 15. Minimum weight with maximum flexure strength is secured by constructing the arm 11 with a section as shown in Figure 3, which is an enlargement of a section taken on line 3—3 of Figure 1. By turning Figure 3 upside down a vertical section through the hook 14 looking toward the outer end 12 is obtained. Since the clearance between the top of railway car wheels and the bodies of railway cars is not uniform, depending on both the load in the car and the design of the specific car, the thickness of the part of the arm member 11 which goes over the flange of the car wheel 15 should be small enough to provide for all cases that may be encountered.

Referring now to Figures 5, 6, and 7, of the drawings, there is shown a stirrup 20 which is adapted to be supported by a flexible cable 21. One end of the cable 21 is secured in an internally conical shaped eye 22 on one end of the stirrup 20. The other end of the cable 21 is secured in another internally conical shaped eye 23 integrally formed on one end of a ladder fastening member 24. The ends of the cable 21 may be secured in the eyes 22 and 23 by casting them therein in solder. Figure 9 of the drawings shows the manner in which the ends of the cable 21 are secured. The eye 23 is integrally formed on the ladder fastening member 24 as shown in Figure 7. The ladder fastening member 24 has studs or pins 25 extending therethrough and spaced therealong. A slotted cap 30 is formed integrally on the end of the stirrup 20 opposite the eye 22 into which the ladder fastening member 24 may be slipped so as to have the pins 25 bearing on its underside. By referring to Figures 8 and 9 of the drawings,

the manner in which the ladder fastening member 24 is secured will be more clearly understood. A platform 31 is formed on the stirrup 20 for holding a hydraulic jack 32 as shown in Figures 8 and 9. The ears 33 and 34 are provided on the sides of the platform 31 to keep the jack 32 in place. The strength of the stirrup 20 is provided for by the web construction on its underside as shown in Figure 6.

10 In order that the operation of my hoisting apparatus may be more fully understood, reference may now be had to Figures 8 and 9 of the drawings. When it becomes necessary to remove the journal brass 35 of a journal box 36, the first 15 step in using my hoisting apparatus is to place the arm member 11 in position on the top of the car wheel 15. The cable 21 is then placed in the groove 13 on the outer end 12 and the jack 32 is placed in the stirrup 20 with its handle 37 toward 20 the outside. The jack 32 is then held in position beneath the journal box 36 with its piston 41 thereagainst and the ladder fastening member 24 is slipped into position in the slotted cap 30, taking up as much slack in the cable 21 as is 25 convenient. My hoisting apparatus is now in place and assembled for lifting the journal box 36. The jack 32 which is preferably hydraulic is provided with a valve 40 which must be closed in order that the piston 41 may be raised and 30 which must be opened in order to let down the piston 41 after it has been raised. After closing the valve 40, the operator operates the handle 37 thereby operating the jack 32 and raising the piston 41. As soon as all of the slack in the 35 cable 21 has been taken up, the journal box 36 will commence to be lifted thus taking the load off of the journal brass wedge 42 and in turn the journal brass 35. By having the door 43 of the journal box 36 lifted, the operator can look in and observe the progress being made in lifting the journal box 36 and can see when the journal brass wedge 42 is free to be removed. When it is 40 observed that the journal brass wedge 42 is free it may be then pulled out of the journal box 36 by a hook 44 and the journal brass 35 can be removed thereafter. After the journal brass 35 has been replaced and the journal brass wedge 42 properly inserted in the journal box 36, the 45 valve 40 may be opened and the piston 41 thereby released allowing the journal box 36 to be lowered. After the journal box is once more resting on the wedge 42, the hoisting apparatus can then be removed.

It will be seen that the load of the lifted journal box 36 is carried as follows: the load is transferred through the jack 32 to the stirrup 20, the 50 load on the stirrup 20 is supported by the cable 21, the load on the cable 21 is supported from the outer end 12 of the arm member 11 and the load on the arm member 11 is supported at the 55 bearing surface 17 bearing against the tread 18 of the wheel 15. It is further seen that the moment of the load on the outer end 12 about the bearing surface 17 is counterbalanced by the hook 14 gripping into the inside of the wheel 15.

By having the load of the lifted journal box 60 36 transferred to and carried by the wheel 15,

it serves to hold the wheel 15 in place and to prevent it from rising off the track or slipping sidewise.

In the event that it may for some reason be impossible to employ my hoisting apparatus for lifting a journal box 36 as outlined above, it is possible to jack up the journal box 36 in the conventional manner. This is illustrated in Figure 10 of the drawings. As there shown, the arm member 11 is placed beneath the journal box 36 10 with its outer end 12 resting on the lower inside of the wheel 15 and with the hook 14 resting on a block 50. The inner contour of the arm member 11 is such that the jack 32 can be placed thereon as shown for jacking up the journal box 15 36. Thus it will be seen that my hoisting apparatus may be used in practically any situation for lifting a journal box to remove the journal brass therefrom.

It will be observed that it is preferable to make 20 the outer end 12 of the arm member 11 approximately the same width as the stirrup 20. However, this is a matter of design and may be varied.

It will also be understood that the hydraulic jack 32 may be replaced by other types and that 25 the cable 21 may be replaced by a chain or other support means.

Since certain further changes can be made in the foregoing construction, and different embodiments of the invention may be made without departing from the scope thereof, it is intended that all matter shown in the accompanying drawings or described hereinbefore shall be interpreted as illustrative, and not in a limiting 30 sense. 35

I claim as my invention:

1. Railway car journal hoisting apparatus comprising, in combination, an arm adapted to be supported by a railway car wheel and to project over the journal box of said railway car wheel, a stirrup, a flexible cable for supporting said stirrup from said arm, one end of said cable being secured to one end of said stirrup and the other end attached to a ladder fastening member adapted to adjustably fasten said other end to said stirrup, and a jack carried in a platform on said stirrup for lifting said journal box, the load of said lifted journal box being transferred through said jack to said stirrup, the load on said stirrup being supported by said flexible cable which in turn is supported from the outer end of said arm, the load on said outer end being supported on the tread of said railway car wheel and the moment of the downward load on the outer end of said arm about the tread support being counterbalanced by a hook of said arm which securely grips into the inside of said railway car wheel. 50 55

2. A stirrup for use in connection with railway car journal hoisting apparatus having a 60 platform for carrying a jack and adapted to be supported by a cable one end of which is secured to one end of said stirrup and a slotted cap integrally formed on the opposite end of said stirrup by which the other end of the cable is secured. 65

AUGUST W. DONOP.
